(57) **CLAIM**

We claim the ornamental design for a display screen or portion thereof with graphical user interface, as shown and described.

DESCRIPTION

FIG. 1 is a front view of a display screen or portion thereof with graphical user interface; and,
 FIG. 2 is a front view of FIG. 1 depicted on a device.
 The broken lines in the drawings illustrate portions of the display screen or portion thereof with graphical user interface that form no part of the claimed design.
